CLAIM

The ornamental design for a cable management system, as shown and described.

DESCRIPTION

FIG. 1 is a left, front, top perspective view of the cable management system;

FIG. 2 is a left, rear, bottom perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top view thereof;

FIG. 8 is a bottom view thereof;

FIG. 9 is a left, front, top perspective view of an exploded view thereof;

FIG. 10 is a left, rear, bottom perspective view the exploded view thereof;

FIG. 11 is a front elevation view of the exploded view thereof;

FIG. 12 is a rear elevation view of the exploded view thereof;

FIG. 13 is a left elevation view of the exploded view thereof;

FIG. 14 is a right elevation view of the exploded view thereof;

FIG. 15 is a top view of the exploded view thereof; and,

FIG. 16 is a bottom view of the exploded view thereof.

The shade lines in the Figures show contour and not surface ornamentation.

The broken lines and unshaded areas within them in FIGS. 1-16 showing portions of the cable management system are included for the purpose of illustrating environment that do not form a part of the claimed design.

1 Claim, 16 Drawing Sheets
